DESIGN FOR A CAMERA

Frank A. Robinton, Hartford, Conn., assignor to
Universal Camera Corporation, New York,
N. Y., a corporation of Delaware

Application July 25, 1939, Serial No. 86,231

Term of patent 7 years

To all whom it may concern:

Be it known that Frank A. Robinton, a citizen of the United States and resident of Hartford, in the county of Hartford and State of Connecticut, has invented a new, original, and ornamental Design for a Camera, of which the following is a specification, reference being had to the accompanying drawing, forming part thereof, in which,

Fig. 1 is a perspective view of a camera embodying my new design;

Fig. 2 is a front elevational view thereof;
Fig. 3 is a top plan view thereof; and
Fig. 4 is a side fragmentary elevational view
thereof, showing the side not visible in Fig. 1.
The dominant features of the design reside
in portions shown in full lines.

I claim:

The ornamental design for a camera, substantially as shown and described.

FRANK A. ROBINTON.
